UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

FEEDING MECHANISM FOR SEWING MACHINES

Application filed February 15, 1926. Serial No. 88,298.

The invention relates to new and useful improvements in feeding mechanisms for sewing machines, and more particularly to a feeding mechanism used in connection with 5 a work supporting arm for feeding the material lengthwise of the arm.

Work supporting arms have been mounted at the upper end of a post and also at the lower end of a depending vertical member 10 so as to provide a suspended arm around which the material being sewed can be placed. In machines of this type, the feeding mechanism and looper mechanism are located in the work supporting arm, and the actuating 15 devices therefor extend through the supporting member or the vertical post.

An object of the present invention is to provide a machine of the type wherein the work supporting arm is suspended from a 20 depending vertical member, and wherein the arm is detachably connected to the lower end of said vertical member and contains the feeding mechanism and the looper mechanism which are actuated by parts in the vertical member; the devices for connecting the parts in the vertical member to the feeding mechanism and the looper mechanism in the work supporting arm are supported by a detachable arm, so that said detachable arm and 25 the immediate actuating mechanism for the feeding mechanism and the looper mechanism can be assembled in said arm and attached to or removed from the sewing machine proper as a unit.

30 A further object of the invention is to provide a feeding mechanism for a work supporting arm of the above type wherein the actuating mechanism includes parts mounted on a cross shaft located at the upper end 35 of the detachable work supporting arm and directly beneath the vertical member which supports the same.

A still further object of the invention is to provide a machine of the above type 40 wherein said stationary cross shaft carries an oscillating sleeve for imparting the back and forth movements to the feed bar, and wherein a second oscillating sleeve is mounted on the first oscillating sleeve for imparting back and forth movements to the looper 45

supporting shaft, said sleeves being oscillated by eccentrics on the main shaft directly above the parts to which they are connected, said eccentrics being mounted on an actuating shaft extending at an acute angle 55 to the longitudinal axis of the work supporting arm.

A further object of the invention is to provide a machine of the above type wherein the eccentric for moving the feed bar back and forth is capable of adjustment on an actuating shaft for the purpose of varying the stroke of the feed bar.

A further object of the invention is to provide a machine of the above type wherein the feed bar has a relatively wide end for supporting the feed dog so as to prevent any tilting or cramping of the parts during the feed operation.

A further object of the invention is to provide a feeding mechanism for a work supporting arm wherein the feed bar extends lengthwise of said arm with eccentric members for supporting the opposite ends of said feed bar which can be adjusted for leveling 70 the feed bar, and which eccentric members are accessible so that they may be adjusted at any time by the operator after the parts have been assembled in the machine.

These and other objects will in part be obvious and will in part be hereinafter more fully disclosed.

In the drawings which show by way of illustration one embodiment of the invention—

Figure 1 is a view partly in perspective and partly in section showing a machine embodying the improvements;

Fig. 1^a is a view partly in side elevation and partly in section showing the detached work supporting arm and the actuating devices for the feed and the looper as disconnected from the main actuating shaft;

Fig. 2 is a plan view of the detached work supporting arm with the eccentric straps, the cover plate and the end cap for the looper removed;

Fig. 3 is a sectional view on the line 3—3 of Fig. 2;

Fig. 9 is a view partly in section on the line 9, 9 of Fig. 8 and partly broken away, on an enlarged scale, showing the eccentric for actuating the feed bar and the adjustable support therefor.

The invention is directed broadly to a feeding mechanism for a sewing machine having a suspended work supporting arm, and preferably a machine of the type shown in the Patent No. 1,741,095, granted Christensen and Le Vesconte, Dec. 24, 1929. The machine of the present application includes a supporting base or frame 1 which is provided with an overhanging portion at the upper end to which the main frame 2 of the machine is integrally attached. The supporting base is attached to said main frame at both ends thereof. Located in this main supporting frame 2 is a main actuating shaft 3 which is driven by a belt wheel 4. Projecting forwardly from the left-hand side of the frame 2 is a housing 5 in which the needle bar 6 reciprocates, said needle bar carrying needles 7, 7. A presser bar 8 is also located in this housing and carries a presser foot 9.

At the right-hand end of the frame 2 there is a depending member 10. The supporting base 1, the frame 2, the depending member 10, and a portion of the housing 5, are all cast as one integral piece.

The main shaft 3 is mounted in suitable bearings, one of which is shown in section in Fig. 1 at 11. The depending member 10 terminates on the line α — α (see Figures 1 and 6).

Attached to the lower end of this depending member 10 is the work supporting arm 12. Said work supporting arm 12 is substantially cylindrical in form, and extends from a point directly beneath the vertical member 10 to a point beneath the needle bar 6. Inasmuch as the frame 2 is directly above the depending member 10, and the needle bar is offset from this frame 2, as it is mounted in the forward end of the laterally projecting housing 5, the work supporting arm 12 necessarily extends in a direction at an acute angle to the actuating shaft 3. This work supporting arm 12 is suspended so that there is a clearance underneath the same and a clearance between said arm and the supporting base 1. The material to be stitched may be

passed underneath said work supporting arm and folded up around the arm so as to stitch a tubular member, and as the tubular member is stitched, it is passed off the end of the work supporting arm. The fabric forming the tubular member will, of course, be folded up around the portion of the arm which projects from the depending member 10. The work supporting arm extends all the way across the lower end of the depending members and projects therefrom to provide a work supporting portion. The work supporting arm is secured to the depending member by means of screws 13, 13 which are passed through lugs 14 cast with the lower end of the depending member 10 and are threaded into the work supporting arm.

Located in this work supporting arm is a feed bar 15 which extends longitudinally of the work supporting arm. Said feed bar 15 carries a feed dog 16 having feeding teeth formed so as to feed the material off from the end of the work supporting arm. Said feed bar at the extreme left-hand end thereof is provided with a very much broadened face 17. The feed dog 16 has a broadened shank 18 which rests on this broadened face 17 of the feed bar, and said shank is secured thereto by screws 19, 19. This makes a very wide and durable support for the feed dog. The work supporting arm is provided with spaced faces 20, 20 between which the free end of the feed bar reciprocates back and forth. This feed bar 15 is mounted at its forward end on a swinging link 21. The feed bar is pivoted at 22 to said swinging link. The swinging link in turn is pivoted at 23 to a lever 24, which lever extends longitudinally of the work supporting arm and to a point in the arm beneath the depending member 10. At its inner end, which is the right-hand end as viewed in Fig. 1, there is a ball stud 25 to which an eccentric strap 26 is connected. This eccentric strap 26 cooperates with an eccentric 27 on the main shaft 3. The lever 24 is fulcrumed on a pin 28 shown in perspective in Fig. 5, and provided with an eccentric portion 29 and with a slotted head 30. This eccentric pin is accessible from the outside of the work supporting arm. A set screw 31 holds the eccentric pin in adjusted positions. When it is desired to raise the front end of the feed bar, this set screw 31 is released, and the operator, by the aid of a screw driver, can turn the eccentric pin so as to raise or lower the free end of the lever 24, and this in turn will raise or lower the free end of the feed bar 15.

The rear end of the feed bar is mounted on a swinging link 32. This swinging link 32 is provided with two upwardly extending arms 33, 33 which extend on opposite sides of the feed bar 15, and are secured thereto by means of a pivot screw 34. The lower end of the link is mounted on an eccentric pin 35 which

is of the construction of the eccentric pin shown in Fig. 5. This eccentric pin 35 is held in adjusted positions by a set screw 36. By adjusting this eccentric pin 35, the rear end of the feed bar can be raised or lowered. Through the use of these two eccentric pins above referred to, the feed bar may be either raised or lowered at either end thereof, and one end may be raised while the other end is lowered. This provides a means whereby the feed bar can be raised and lowered so as to vertically adjust the longitudinal axis of the path of travel of the feed dog or so as to incline said axis. By this means, the working position of the feed dog can be varied, and the feed dog maintained level or inclined, as desired. The present machine is provided with only one feed dog, and is especially adapted for operating upon non-elastic fabrics. Even non-elastic fabrics are sometimes stretchable, and it is desired to incline the feed dog so as to crowd the material forward to avoid the material from being stretched as it is stitched. On the other hand, it is sometimes desirable to incline the feed dog in the opposite direction so as to draw the material away from the stitching point and prevent puckering or gathering of the same during stitching. This can all be accomplished by the adjustment of the two eccentric pins which have just been described.

The feed bar is moved back and forth on the swinging links by means of a link 37 which is pivoted at 38 to the rear end of the feed bar. The other end of this link is pivoted at 39 to a depending arm 40. Mounted in the detachable work supporting arm 12 and midway between the front and rear sides of the depending member 10, is a stationary cross shaft 41. Said cross shaft is fixed in its supporting bearings by means of set screws 42. Mounted on this stationary cross shaft is a sleeve 43 (see Fig. 6). Clamped to this sleeve 43 is a split collar 44 with which said arm 40 is integrally formed. A clamping bolt 45 serves to attach said split collar to the sleeve 43. Said sleeve is also provided with a laterally projecting arm 46 carrying a ball to which an eccentric strap 47 is attached. This eccentric strap 47 cooperates with an eccentric 48 on the main shaft 3. As the main shaft rotates, the eccentric strap 47 will oscillate the sleeve 43, and said oscillations of the sleeve 43, through the arm 40 and link 37, will move the feed bar back and forth. The eccentric 48 is in the form of a ring (see Fig. 7), which ring is pivoted at 49 to a lug carried by the collar 50, which collar 50 is secured to the shaft 3 by means of screws 51. The eccentric has a segmental recess 52 formed therein, and a slot 53 leading from the bottom of said recess to the inner face of the ring. A screw 54 extends through said slot and is threaded into the sleeve 50. This screw is readily accessible through an open-

ing 54^a in the eccentric strap when the actuating shaft is stopped with the screw beneath said opening. By loosening the screw, the eccentric can be adjusted about its pivotal support on the sleeve, and then the eccentric can be again secured in its adjusted position. The bottom of the recess is formed about the pivot point 49 as a center. The side face of the eccentric is provided with radial grooves 48^a. When the cover plate 78 is removed, an instrument such as a small screw driver can be passed down alongside of the bearing 11 in which the main shaft 3 is mounted, and engage these grooves so as to adjust the eccentric without removing the eccentric strap. 75

Through the above structure, the eccentric is capable of adjustment on the main shaft so that the throw of the eccentric can be varied. When the throw is increased, then the stroke of the feed bar will be increased, and when the throw of the eccentric is decreased, then the stroke of the feed bar will likewise be decreased. 85

Extending lengthwise through the work supporting arm is a looper supporting shaft 55 on which a looper carrier 56 is mounted, and said looper carrier is provided with two loopers 57, 57. These loopers are of the thread carrying type and are oscillated into and out of the needle thread loops, and are moved laterally to avoid the needle after the manner common with thread carrying loopers. The shaft is mounted in suitable bearings 58 and 59 which are cast integral with the work supporting arm, and also in a bearing 60 which is removably attached to said work supporting arm at the rear end of the shaft. On the rear end of the looper supporting shaft there is a crank arm 61 carrying a ball stud 62. A link 63 cooperates with said ball stud 62 at the lower end of the link. On the extreme right-hand end of the actuating shaft 3 there is an eccentric 64 with which an eccentric strap 65 cooperates. Mounted on this eccentric 64 is a ball stud 66 which is offset from the center of the shaft 3. The upper end of the link 63 cooperates with this ball stud 66. Attached to the ball stud at the outer end thereof is a rectangular block 67. Said block is secured to the stud by a screw 68. Attached to the link 63 is a bracket 69, which is forked at the upper end and straddles said rectangular block 67. The purpose of this bracket is to prevent the link 63 from oscillating on the ball studs to which it is attached. This link 63 oscillates the looper shaft and causes the loopers to move into and out of the needle thread loops. Mounted on the looper supporting shaft are two spaced collars 70 and 71. These collars are fixed to the looper supporting shaft. Between said collars is a sleeve 72 which is freely supported on the looper shaft. Said sleeve has an upwardly projecting arm 73. Links 74 are pivotally 130

connected to said arm at opposite sides thereof. Mounted on the sleeve 43 is a second sleeve 75. Said second sleeve is freely mounted on the first-named sleeve and can oscillate thereon. Said second-named sleeve is provided with a depending arm 76, and the links 74 are pivotally connected at the other ends thereof with this depending arm 76. Said sleeve 75 has a laterally projecting arm 77 carrying a ball head with which the eccentric strap 65 is connected. Thus it is that the eccentric 64 on the main shaft 3 oscillates the sleeve, and the sleeve, through its connection with the looper supporting shaft, moves said shaft endwise in the work supporting arm. This imparts the lateral or needle avoiding movements to the loopers. The eccentrics 27, 48 and 64 are all connected by spot screws to the main shaft 3, and when these spot screws are loosened, the shaft can be withdrawn from the eccentrics. The depending member 10 and main frame 2 are provided with a removable cover plate 78. After the spot screws holding the eccentrics have been loosened, the main shaft can be moved endwise to the left as viewed in Fig. 1, and withdrawn from the eccentrics. The work supporting arm 12 has an opening 79 formed therein, through which the looper supporting shaft 55 may be inserted during the assembling of the parts. As clearly shown in Fig. 1, the work supporting arm 12 can be readily detached from the main frame of the machine, after the eccentric straps have been disconnected from the main shaft of the machine. In other words, the feed bar and the looper supporting shaft are mounted in the work supporting arm and extend lengthwise thereof. The actuating devices between the eccentric straps and the links which impart movements to the feed bar and looper, are all mounted in the work supporting arm so that after the eccentric straps are disconnected from the main shaft, said arm with the eccentric straps can be removed from the machine. On the other hand, the feed bar, looper shaft and actuating devices therefor, can all be assembled in the detached work supporting arm, after which the work supporting arm can be connected to the main frame, the eccentric straps connected to the main actuating shaft, and the machine is assembled. It will readily be seen that there is a great advantage in the detachable arm in the casting of the parts of the main frame. There is a further advantage in the ability to assemble the parts in the work supporting arm before it is attached to the main frame of the machine. The machine so far described is particularly adapted for operating upon non-elastic materials, such as are used in the making of overalls and the like. This machine is likewise intended to be used for knit work, where the material is elastic, and where it is also

desirable to use a differential feeding mechanism. The differential feeding mechanism may be likewise assembled in the work supporting arm in the place of the single feed bar and feed dog illustrated, and the detached arm attached to the main supporting frame of the machine. In other words, the main frame may be used as a standard frame for the assembling of machines of different types, due to the fact that the work supporting arm is removable as a unit, and another work supporting arm with different mechanism assembled therein, may be substituted therefor.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A sewing machine including in combination a main frame having a depending member open at its lower end a main shaft carried by said frame and extending over said depending member, a work supporting arm, means for detachably securing said work supporting arm to the lower end of said depending member with said arm extending at right angles to the depending member, a stationary shaft mounted in said work supporting arm directly beneath the depending member, a feed bar extending lengthwise of said work supporting arm, an oscillating sleeve mounted on said stationary shaft, an arm projecting from said sleeve, means for connecting said arm to said feed bar for moving the feed bar endwise, a second arm carried by said sleeve, a vertically reciprocating member in said depending member connected to said second arm for oscillating the sleeve and an eccentrically arranged member on said main shaft to which said vertically reciprocating member is connected whereby said vertically reciprocating member when detached from said eccentrically arranged member together with the parts operated thereby and the work supporting arm in which they are disposed, may be removed as a unit.

2. A sewing machine including in combination a main frame having a depending member open at its lower end a main shaft carried by said frame and extending over said depending member, a work supporting arm, means for detachably securing said work supporting arm to the lower end of said depending member with said arm extending at right angles to the depending member, a stationary shaft mounted in said work supporting arm directly beneath the depending member, a feed bar extending lengthwise of said work supporting arm, an oscillating sleeve mounted on said stationary shaft, an arm projecting

- from said sleeve, means for connecting said arm to said feed bar for moving the feed bar endwise, a second arm carried by said sleeve, a vertically reciprocating member 5 in said depending member connected to said second arm for oscillating the sleeve, a looper shaft extending lengthwise of said work supporting arm, a second sleeve mounted on said first-named sleeve, said second sleeve having a projecting arm, means for connecting said projecting arm to said looper supporting shaft for moving said shaft endwise, said second sleeve having a second 10 projecting arm, a vertically reciprocating member located in said depending member and connected to said second arm for oscillating the same, and eccentrically arranged members on said main shaft with which said vertically reciprocating members respectively cooperate whereby when said vertically reciprocating members are detached from the eccentrically arranged members, said vertically reciprocating members together with the parts actuated thereby and the work supporting arm may be removed as a unit. 15
3. A sewing machine including a main frame having a main operating shaft located therein, said frame having a depending member, a work supporting arm connected to the lower end of said depending member, a feed bar extending lengthwise of said work supporting arm, actuating means for said feed bar including an eccentric on the main shaft, said eccentric including a ring-shaped member, a sleeve having a projecting lug to which said ring-shaped member is pivoted, said sleeve being fixed to the actuating shaft for the eccentric, said ring-shaped member having a segmental slot extending therethrough, a screw located in said slot and adapted to engage said sleeve for holding said ring in various adjusted positions on said sleeve, for varying the throw of said eccentric, said actuating devices including an eccentric strap cooperating with said eccentric, said strap having an opening therethrough, whereby said screw is accessible for adjusting the eccentric without removing the eccentric strap. 20
4. A sewing machine including a main frame having a main operating shaft located therein, said frame having a depending member, a work supporting arm connected to the lower end of said depending member, a feed bar extending lengthwise of said work supporting arm, a feed bar including an eccentric on the main shaft, said eccentric including a ring-shaped member, a sleeve having a projecting lug to which said ring-shaped member is pivoted, said sleeve being fixed to the actuating shaft for the eccentric, said ring-shaped member having a segmental slot extending therethrough, a screw located in said slot and adapted to engage said sleeve for holding said ring in various adjusted positions on said sleeve, for 25
- varying the throw of said eccentric, said actuating devices including an eccentric strap cooperating with said eccentric, said strap having an opening therethrough, whereby said screw is accessible for adjusting the eccentric without removing the eccentric strap, 30 said eccentric having radial grooves formed in the side face thereof to aid in the positioning of the eccentric during the adjustment thereof. 35
5. A feeding mechanism for sewing machines including a work supporting arm, a feed bar in said arm extending longitudinally thereof, a feed dog carried by said feed bar, means for supporting said feed bar whereby the same may be moved endwise of the work supporting arm, said supporting means including eccentric members accessible from the outside of the work supporting arm whereby said feed bar may be raised or lowered at either end thereof. 40
6. A feeding mechanism for sewing machines comprising a work supporting arm, a feed bar extending lengthwise of said arm, a feed dog carried thereby, swinging members located adjacent the opposite ends of said feed bar for supporting the same, whereby said feed bar may be moved lengthwise of the work supporting arm, an eccentric member for supporting each swinging member, accessible from the outside of the work supporting arm, and adjustable whereby said feed bar may be raised or lowered at either end thereof. 45
7. A feeding mechanism for sewing machines comprising a work supporting arm, a feed member extending lengthwise of said work supporting arm, a feed dog carried thereby, a lever extending lengthwise of said work supporting arm, a vertical link connecting the forward end of the lever with the forward end of the feed bar, an eccentric member on which said lever is fulcrumed, means accessible from the outside of said work supporting arm for adjusting said eccentric member, means for holding the eccentric member in adjusted position whereby the forward end of the feed bar may be raised or lowered, a swinging member for supporting the rear end of said feed bar, means connected to the feed bar for moving the same endwise, an eccentric member for supporting said swinging member, means accessible from the outside of said work supporting arm for adjusting said last-named eccentric member, and means for securing said last-named eccentric member in adjusted positions. 50
8. A sewing machine including a main frame having a depending member open at its lower end, a work supporting arm connected to said depending member and closing the lower end thereof, a feed bar extending lengthwise of said work supporting arm, a looper shaft extending lengthwise of said work supporting arm, a lever for raising 55
- 100
- 105
- 110
- 115
- 120
- 125
- 130

and lowering the front end of the feed bar extending lengthwise of said work supporting arm and terminating beneath the depending member, rocking members mounted to swing about a common center in and adjacent the upper edge of the work supporting arm and centrally beneath said depending member, a main actuating shaft in said main frame disposed in the upper end 10 of said depending member, three spaced eccentrics on said main shaft, an eccentric strap cooperating with one eccentric and connected to said lever for oscillating the same, an eccentric strap cooperating with another eccentric and connected to one of said rocking shafts for oscillating the same, and an eccentric strap connected with a third eccentric and with the other rocking shaft for oscillating the same, the connections between the eccentric straps and the lever and rock shafts lying substantially in a line directly beneath the main actuating shaft, said main actuating shaft being disposed in a vertical plane cutting the vertical 20 plane containing the longitudinal axis of the work supporting arm at an acute angle.

9. A sewing machine including a main frame having a depending member open at its lower end, a work supporting arm extending at right angles to said depending member, means for detachably connecting said work supporting arm to said depending member at the lower end thereof, a feeding mechanism located in said arm, reciprocating devices extending through said depending member for operating said feeding mechanism, said feeding mechanism including a feed bar located in and extending lengthwise of said work supporting arm, a 30 rock lever connected to the feed bar for moving said feed bar back and forth, said rock lever being connected to one of said reciprocating devices in said depending member, and means operated by the other reciprocating device in said depending member for raising and lowering said feed bar, all of the said members operated by said reciprocating devices in the depending member being mounted in said work supporting arm 40 whereby the feeding mechanism may be assembled in said work supporting arm and said arm subsequently connected to said depending member.

10. A sewing machine including a main frame having a depending member open at its lower end, a main shaft in said frame extending over the upper end of said depending member, a work supporting arm extending at right angles to the depending member, means for detachably connecting said work supporting arm to said depending member at the lower end thereof, a feeding mechanism supported within said work supporting arm, an eccentric on the main shaft, 50 a reciprocating member operated by said eccentric extending through said depending member and connected to said feeding mechanism for imparting feeding movements thereto, an eccentric member on said main shaft, an eccentric strap cooperating therewith extending through said depending member and connected to said feeding mechanism for raising and lowering the same, a looper mechanism located in said work supporting arm including a looper mounted for oscillation and for lateral movement, an eccentric on said main shaft, a reciprocating member cooperating with the eccentric and extending through said depending member for moving the looper laterally, a crank on said main shaft, a reciprocating member cooperating therewith and extending through said depending member and connected to said looper for oscillating the same, all of the actuated parts of the feeding mechanism and the looper mechanism being supported by said work supporting arm whereby said parts may be assembled in said work supporting arm and the arm subsequently connected to said depending member.

11. A sewing machine including a main frame having a depending member open at its lower end, a work supporting arm extending at right angles to said depending member, means for detachably connecting said work supporting arm to the lower end of said depending member, a feeding mechanism located in said work supporting arm including a feed bar, a rocker for moving said feed bar back and forth and a lever for raising and lowering said feed bar, all of said parts of the feeding mechanism being mounted in and removable with said work supporting arm, a main shaft mounted in said frame at the upper end of said depending member, and devices directly operated by said shaft and connected to said lever and said rocker in the work supporting arm respectively for actuating the feed bar, said devices being free from support by the depending member whereby when disconnected from the main shaft said devices the parts operated thereby and the work supporting arm may be removed as a unit.

12. A sewing machine including a main frame having a depending member open at its lower end, a work supporting arm extending at right angles to said depending member, means for detachably connecting said work supporting arm to the lower end of said depending member, a feeding mechanism located in said work supporting arm including a feed bar, a rocker for moving said feed bar back and forth and a lever for raising and lowering said feed bar, all of said parts of the feeding mechanism being mounted in and removable with said work supporting arm, a main shaft mounted in said frame at the upper end of said depending member, and devices directly operated by said shaft and

connected to said lever and said rocker in the work supporting arm respectively for actuating the feed bar, said main frame having an opening with a cover plate therefor at the upper end of the depending member for rendering the main shaft and interior of said depending member accessible whereby the actuating devices for the feeding mechanism may be disconnected from the main shaft and the work supporting arm, with the feeding mechanism assembled therein, removed as a unit, said devices being free from support by the depending member whereby when disconnected from the main shaft said devices the parts operated thereby and the work supporting arm may be removed as a unit.

13. A sewing machine including a main frame having a depending member open at its lower end, a work supporting arm extending at right angles to said depending member, means for detachably connecting said work supporting arm to the lower end of said depending member, a feeding mechanism located in said work supporting arm including a feed bar, a rocker for moving said feed bar back and forth and a lever for raising and lowering said feed bar, all of said parts of the feeding mechanism being mounted in and removable with said work supporting arm, a main shaft mounted in said frame at the upper end of said depending member, an eccentric mounted on the main shaft, an eccentric strap cooperating therewith and connected to the rocker in said work supporting arm, a second eccentric on said main shaft and an eccentric strap cooperating therewith and connected to the lever in said work supporting arm, said eccentric straps being free from support by the depending member whereby when said straps are disconnected from the eccentrics said straps, the parts actuated thereby and the work supporting arm may be removed as a unit.

14. A sewing machine including a main frame having a depending member open at its lower end, a work supporting arm extending at right angles to said depending member, means for detachably connecting said work supporting arm to the lower end of said depending member, a feeding mechanism located in said work supporting arm including a feed bar, a rocker for moving said feed bar back and forth and a lever for raising and lowering said feed bar, all of said parts of the feeding mechanism being mounted in and removable with said work supporting arm, a main shaft mounted in said frame at the upper end of said depending member, an eccentric mounted on the main shaft, an eccentric strap cooperating therewith and connected to the rocker in said work supporting arm, a second eccentric on said main shaft and an eccentric strap cooperating therewith and connected to the lever in said work supporting arm, a looper shaft mounted in said work supporting arm, a looper carried by said shaft at the free end thereof, the other end of said looper shaft terminating beneath said depending member and having a crank thereon, a rocking member mounted in said work supporting arm directly beneath the depending member and connected to the looper supporting shaft for moving the same endwise, a third eccentric member on said main shaft, an eccentric strap cooperating therewith and connected to said rocking member, a crank carried by the end of said shaft and a link connecting said crank with the crank on the looper shaft for oscillating the same, said eccentric straps being free from support by the depending member when said straps are disconnected from the eccentrics, whereby said straps, the parts actuated thereby and the work supporting arm may be removed as a unit.

15. A sewing machine including a main frame having a depending member open at its lower end, a work supporting arm extending at right angles to said depending member, means for detachably connecting said work supporting arm to the lower end of said depending member, a feeding mechanism located in said work supporting arm including a feed bar, a rocker for moving said feed bar back and forth and a lever for raising and lowering said feed bar, all of said parts of the feeding mechanism being mounted in and removable with said work supporting arm, a main shaft mounted in said frame at the upper end of said depending member, an eccentric mounted on the main shaft, an eccentric strap cooperating therewith and connected to the rocker in said work supporting arm, a second eccentric on said main shaft and an eccentric strap cooperating therewith and connected to the lever in said work supporting arm, a looper shaft mounted in said work supporting arm, a looper carried by said shaft at the free end thereof, the other end of said looper shaft terminating beneath said depending member and having a crank thereon, a rocking member mounted in said work supporting arm directly beneath the depending member and connected to the looper supporting shaft for moving the same endwise, a third eccentric member on said main shaft, an eccentric strap cooperating therewith and connected to said rocking member, a crank carried by the end of said shaft and a link connecting said crank with the crank on the looper shaft for oscillating the same, said eccentric straps being free from support by the depending member when said straps are disconnected from the eccentrics, whereby said straps, the parts actuated thereby and the work supporting arm may be removed as a unit.

16. A sewing machine including a main frame having a depending member open at its lower end, a main shaft in the main frame having a plurality of eccentric members located directly over said depending member, a work supporting arm extending at right angles to the depending member and having a portion thereof conforming to and fitting the lower end of said depending member, securing bolts located within said depending member and detachably connecting said arm to said depending member, a feeding mechanism located in said arm, a looper mechanism located in said arm, actuating devices connected to said eccentric members and extending through said depending member into the work supporting arm and connected to the feeding mechanism and looper mechanism for actuating the same, said actuating devices and said feeding mechanism and said looper mechanism all being supported by said work supporting arm whereby when said actuating devices are disconnected from the eccentric members, said work supporting arm may be removed from the machine as a unit. 70
17. A sewing machine including a main frame having a depending member opening downwardly at its lower end, a work supporting arm located beneath and detachably connected to the lower end of said depending member and extending at right angles to said depending member, means for detachably connecting said work supporting arm to said depending member, a feeding mechanism located in said arm, reciprocating devices extending through said depending member for operating said feeding mechanism, said feeding mechanism including devices for converting the movements of one of the reciprocating devices in said depending member into a horizontal movement for imparting lengthwise movement to the feed bar, said last-named devices being mounted in said detachable work supporting arm whereby said feeding mechanism may be assembled in said work supporting arm and said arm subsequently attached to said depending member. 85
18. A sewing machine including a main frame having a depending member opening downwardly at its lower end, a main shaft in said main frame having a plurality of eccentric members located directly over said depending member, a work supporting arm located beneath and detachably connected to the lower end of said depending member with said arm extending at right angles to said depending member, means for detachably connecting said arm to said depending member, a feeding mechanism located in said arm, a looper mechanism located in said arm, actuating devices connected to said eccentric members and extending through said depending member into the work supporting arm and connected to the feeding mechanism and looper mechanism for actuating the same, said actuating devices and said feeding mechanism and said looper mechanism all being supported by said work supporting arm whereby when said actuating devices are disconnected from the eccentric members, said work supporting arm may be removed from the machine as a unit. 95
19. A sewing machine including a main frame having a depending member opening downwardly at its lower end, a work supporting arm located beneath and detachably connected to the lower end of said depending member and extending at right angles to said depending member, means for detachably connecting said work supporting arm to said depending member, a feeding mechanism located in said arm, reciprocating devices extending through said depending member for operating said feeding mechanism, said feeding mechanism including devices for converting the movements of one of the reciprocating devices in said depending member into a horizontal movement for imparting lengthwise movement to the feed bar, said last-named devices being mounted in said detachable work supporting arm whereby said feeding mechanism may be assembled in said work supporting arm and said arm subsequently attached to said depending member. 105
